UNITED STATES PATENT OFFICE

JOHN R. MITCHELL, OF DALLAS, TEXAS, ASSIGNOR, BY MESNE ASSIGNMENTS, TO THE CAPEHART CORPORATION, OF FORT WAYNE, INDIANA, A CORPORATION OF INDIANA

NEEDLE-CHANGING DEVICE FOR PHONOGRAHS

Application filed August 17, 1928. Serial No. 300,335.

This invention relates to a needle-changing device for phonographs, and has for its object the provision of a hopper for receiving a plurality of needles, and means for aligning said needles and automatically positioning them with their points in proper position to be engaged and clamped in position by the needle-holding mechanism of the reproducer after a record has been played and the used needle discharged therefrom.

One feature of the invention resides in the arrangement for automatically positioning the needles with their points properly located whereby the needles may be deposited promis-
cuously in the hopper and fed in proper position to be inserted in the reproducer.

Another feature of the invention resides in the magazine for conveying the properly positioned needles intermittently in position to be engaged and gripped by the needle-holding mechanism of the reproducer.

Another feature of the invention is the means for actuating the needle-positioning mechanism and the magazine for presenting a new needle by the movement of the tone arm so as to eliminate more complicated driving mechanism.

The full nature of the invention will be understood from the accompanying drawings and the following description and claims:

In the drawings, Fig. 1 is a plan view looking down on the needle-changing mechanism in operative position. Fig. 2 is a side elevation thereof. Fig. 3 is a central vertical section through a portion of the hopper and chute showing a plurality of needles passing therethrough. Fig. 4 is a plan view of the aligning disc. Fig. 5 is a partial elevation illustrating the needle-clamping device. Fig. 6 is a view taken on line 6-6 of Fig. 5.

In the drawings there is shown the supporting table of a phonograph as indicated at 10 upon which is mounted for rotation a turn-table 11. Swivelly mounted upon the table 10 there is a tone arm 12 carrying a reproducer 13 pivotally mounted thereon so as to swing upwardly out of playing position. Said reproducer is provided with a needle-receiving mechanism which comprises a U-shaped tube 14 having the usual connec-

tion with the diaphragm of the reproducer adapted to receive the upper or enlarged portion of the needle. Said U-shaped tube is open on one side so that it may engage the needle sidewise as distinguished from the ordinary practice. Secured on the needle-receiving tube there is a bracket 15 through which a rod 16 extends, the end of said rod being so formed and positioned as to engage the needle 17 and clamp it in position within the tube 14 under the tension of a spring 18.

For arranging and holding the needle in position to be engaged and clamped in the holding tube of the reproducer there is fixedly mounted upon the table 10 a hopper 19 in which a number of needles are carried. One-half of the bottom of the hopper is open, as indicated at 20, and the other half is pro-
vided with a downwardly-extending false bottom 21 for causing the needles to slide into the open portion.

Rotatably mounted in the bottom of the hopper there is an aligning disk 22 adapted to rotate about the hopper and under the false bottom 21, the edge of the false bottom 21 scraping the upper surface of the disk. Said disk is provided with a plurality of perforations 23 extending radially from the center thereof which are just the shape of a needle, having the pointed ends extending outwardly. Said disk is rotated by means of a shaft 24 extending through the main bottom or base 25 of the hopper, which shaft is provided with a pinion 26 adapted to mesh with a rack bar 27 which is slidably supported in a bracket 28 and has one end thereof pivotally connected with the tone arm 12, whereby upon the movement of the tone arm from the outer to the inner portion of the record during the playing thereof, the disk 22 will be slowly rotated in one direction, and upon the movement of the tone arm outwardly to renew the playing action, the disk will be rotated rapidly in the opposite direction.

The rotation of the disk will cause the needles to seek the recesses 23. If the needle finally drops into one of the recesses with its point extending in the proper direction, it will remain therein until it drops through the

100

disk. If it is not properly positioned, a portion thereof will extend upwardly from the disk and be crowded out by the other needles or the edge of the false bottom 21 as the disk is rotated.

Extending downwardly from the open portion of the hopper below the disk there is a chute 29 having an enlarged mouth 30 for receiving the needles as they drop through the openings 23 in the disk 22. The bottom 25 is formed with a shoulder indicated at 31, which temporarily supports the needle in horizontal position until the preceding needle has passed out of the way, whereupon it drops point downward into the chute and passes out through the open end thereof. Said chute terminates and discharges the needles over an annular magazine 32 having a plurality of vertically-extending recesses 33 formed about the periphery thereof, said recesses being of proper size to receive the individual needles which are discharged therein point downward by the rotation of the magazine as each empty recess comes under the chute 29. The needles are maintained in their respective recesses 33 by a spring band 34 which has a mouth 35 formed with outwardly turned resilient lips, which permits the lateral bodily removal of the needle by the receiving tube 14.

For rotating the magazine 32 there is provided about the periphery thereof the ratchet teeth 36 adapted to be engaged by a projecting rod 37 on the reproducer, whereby each movement of the reproducer to engage and remove a needle will cause a rotary movement of the magazine sufficient to bring the following needle into position and bring the emptied recess under the chute 29. The table 10 is provided with a lug 38 against which the rod 16 contacts upon the reproducer swinging to needle-changing position. Upon the engagement of the lug, the rod 16 is moved to release the needle within the holding tube 14 and cause it to drop into a receptacle positioned in the table 10 and thereby make room for a new needle which will be engaged by the tube and clamped therein upon the arm 16 disengaging the lug 38.

From the foregoing, it will be noted that the operator may throw a handful of needles into the hopper 19 and upon the completion of each record, the needle-holding tube 14 will permit the used needle to fall therefrom by gravity and will receive a new needle from the magazine 32.

The invention claimed is:

1. A needle changing mechanism for phonographs including a hopper for receiving a plurality of needles, a movable disk at the bottom of said hopper having a plurality of openings therein for receiving said needles only with their points extending in a given direction, a chute for receiving said needles upon passing through the openings in said

disk, and a magazine adapted to receive the needles from said chute and support them with their points extending in the same direction.

2. A needle changing mechanism for phonographs including a hopper for receiving a plurality of needles, a false bottom for closing a portion of the bottom of said hopper leaving an opening therein through which the needles may pass, a movable disk mounted immediately below said bottom so as to engage the open edge thereof, said disk being provided with a plurality of openings for permitting needles to pass through upon the pointed ends of the needles extending into the pointed ends of the openings, and a magazine for receiving the needles upon passing through said openings whereby they will be supported with their points extending in the same direction. 70

3. A needle changing mechanism for phonographs including a hopper for receiving a plurality of needles, a movable member movable with respect to the bottom of said hopper and provided with a plurality of openings corresponding to the shape of a needle, said openings being so arranged as to permit a needle to pass therethrough only upon the pointed end of the needle being properly positioned with respect to the pointed end of the opening, means for moving said member, and a magazine adapted to receive the needles passing through said openings for supporting them with their points extending in the same direction. 80

4. A needle changing mechanism for phonographs including a hopper for receiving a plurality of needles, a movable member in the bottom of said hopper having a plurality of openings therein, said openings having the same formation as a needle and being so positioned as to permit needles to pass therethrough only when their points extend in a given direction, means for operating said member, and a magazine provided with a plurality of spaced downwardly extending recesses for receiving said needles passing through said member with their points extending in the same direction. 90

5. A needle changing mechanism for phonographs including a hopper for receiving a plurality of needles, a movable member in the bottom of said hopper having a plurality of openings therein, said openings having the same formation as a needle and being so positioned as to permit needles to pass therethrough only when their points extend in a given direction, means for operating said member, a magazine provided with a plurality of spaced downwardly extending recesses for receiving said needles passing through said member with their points extending in the same direction, and a chute connected with said hopper for guiding the needles into said magazine. 100

6. In a phonograph, the combination with a tone arm, of a needle changing mechanism including a hopper adapted to receive a plurality of needles, a movable needle sorting member provided in the bottom of said hopper having a plurality of openings through which the needles are permitted to pass only when their points extend in a given direction, and means operatively connecting the tone arm with said member for causing the same to be actuated through the movement of the tone arm.
7. In a phonograph, the combination with a tone arm, of a needle changing mechanism including a hopper, movable means in said hopper for sorting the needles contained therein so as to cause their points to extend in a given direction, and means operatively connecting said member and tone arm for causing said member to be moved by the swinging action of the tone arm.
8. In a phonograph, the combination with a tone arm and a reproducer thereon, of a needle changing mechanism including a hopper for containing a plurality of needles, a magazine for receiving said needles from said hopper and delivering the same to said reproducer, a movable member associated with said hopper for positioning the needles with their points extending in a given direction, and means connecting said tone arm and member for causing the latter to be operated by the swinging movement of the tone arm.
9. In a phonograph, the combination with a tone arm and a reproducer thereon, of a needle changing mechanism including a hopper for containing a plurality of needles, a magazine for receiving said needles from said hopper and delivering the same to said reproducer, a movable member associated with said hopper for positioning the needles with their points extending in a given direction, and means actuated by the swinging movement of the tone arm for operating said member and moving said magazine in position to bring a new needle into engagement with said reproducer.
10. In a phonograph, the combination with a swinging tone arm and a reproducer carried thereby, of a needle changing mechanism including a hopper adapted to receive a plurality of needles, a rotating disk mounted in the bottom of said hopper, said disk having a plurality of openings through which said needles are adapted to pass only upon their points extending in a given direction, a magazine having a plurality of needle receiving pockets formed therein, a chute for directing the needles passing through said disk, points foremost, into said pockets, a clamping member on said reproducer for engaging and clamping a new needle as presented thereto by said magazine, and a common means for actuating said disk and magazine.
11. In a phonograph, the combination with a swinging tone arm and a reproducer carried thereby, of a needle changing mechanism including a hopper adapted to receive a plurality of needles, a rotating disk mounted in the bottom of said hopper, said disk having a plurality of openings through which said needles are adapted to pass only upon their points extending in a given direction, a magazine having a plurality of needle receiving pockets formed therein, a chute for directing the needles passing through said disk, points foremost, into said pockets, a clamping member on said reproducer for engaging and clamping a new needle as presented thereto by said magazine, and a common means for actuating said disk and magazine.
